APPARATUS FOR DIELECTRIC HEATING

Milton P. Vere, Catonsville, and Robert E. Kirby,
Baltimore, Md., assignors to Westinghouse
Electric Corporation, East Pittsburgh, Pa., a
corporation of Pennsylvania

Application October 12, 1948, Serial No. 54,032

17 Claims. (Cl. 219-47)

1

Dielectric heating usually involves a pair of spaced relatively insulated electrode means between which a high frequency electric field can be established. Dielectric material placed in, or moving through, this field will be heated. A common form of apparatus for such heating on a large scale includes one or more dielectric-heating electrodes of considerable expanse or area. In its broadest aspect, our invention relates to improvements in this field of dielectric heating. In its more limited aspects, our invention relates to improved dielectric heating apparatus of the aforesaid type which utilizes an improved dielectric-heating electrode for obtaining improved results and operations of the apparatus for certain purposes.

In a more specific form of dielectric heating apparatus, dielectric material is carried on a conveyor between a pair of horizontal electrode means, and an air space is provided between the material and the upper dielectric-heating electrode. Under certain circumstances, an electric arc will form in the air-gap between the material and the electrode. Such arcing has occurred in the edge-gluing together of pieces of wood boards, or veneering; by a veneer, etc. meaning any one of a plurality of wood boards or wood pieces, regardless of size or area, that are to be glued together. The arcing may be due to glue drops that are present on the top layer of a stack of veneers or are squeezed out of joints of veneers to be edge glued. If the dielectric-heating electrode has a physically continuous surface, as is usually the case, the arc travels along with the material and damage thereto may result.

An object of our invention is to provide a dielectric heating apparatus in which such objectionable arcing is minimized. In achieving this object we provide a dielectric-heating electrode which electrically presents a substantially flat surface for the high-frequency electric field, but which physically presents a discontinuous surface for interrupting any arc that strikes in the air-gap between the material being heated and the upper dielectric-heating electrode.

In the aforesaid dielectric heat-treatment for edge-gluing pieces of wood boards together, the pieces are clamped with glue between their facing edges. The clamping is maintained during the process, at least until the glue or adhesive at the joints has set sufficiently to make clamping unnecessary for holding the pieces together. In commercial production, pieces of wood stock occasionally buckle out of the clamps. Our improved apparatus is so built that buckled wood

2

stock usually has no damaging effect on the dielectric-heating electrode, although the surface of the upper one is physically discontinuous.

Another object of our invention is to provide a novel dielectric-heating electrode which can have its effective area for bounding a high-frequency electric field readily and simply adjusted.

An ancillary object of our invention is to provide a dielectric-heating apparatus of a type described having a pair of spaced electrode means providing a horizontal work-receiving passage therebetween. The upper electrode-means comprises a novel adjustable dielectric-heating electrode which covers a substantial but adjustable area along the work-receiving passage, but which is mechanically stiff and will not sag in any of the different adjustments of the novel dielectric-heating electrode. As a result, the top of the work-receiving passage defined or bounded by the electrode will be consistently flat, in effect.

Our novel dielectric-heating electrode is distinguished by a plurality of thin flat bars for the electrically active surface of the electrode. The bars are spaced but are close enough to each other to provide, in effect, a continuous electric field along the passage occupied by the work or material being heat-treated. For apparatus using a work-carrying conveyor, the bars extend oblique to the path of travel for the material passing them. Preferably, a plurality of additional similar bars are provided which criss-cross the first-mentioned bars. The two groups of bars are thin and pivotally connected so as to form, in effect, a lazy-tong arrangement which is expandable and contractible within limits. Preferably, the lazy-tong arrangement is supported at a plurality of different points sufficient in number to limit any tendency of the thin pivoted bars to sag.

Objects, features and innovations of our invention, in addition to those specifically set forth above, will be discernible from the following description which is to be taken in conjunction with the accompanying drawings. In these drawings, like reference numerals refer to parts having the same appearance. In the drawings, which are on different scales:

Fig. 1 is an elevational view of an embodiment of our invention incorporating our novel dielectric-heating electrode;

Fig. 2 is an elevational view of another embodiment of our invention incorporating our novel dielectric-heating electrode, this view showing the dielectric-heating electrode as it appears when viewed at a right angle to its showing in Fig. 1;

Fig. 3 is a plan view of the preferred form of our novel dielectric-heating electrode shown in Figs. 1 and 2;

Figs. 4 and 5 are detailed sectional views on the lines IV—IV and V—V of Fig. 3; and

Figs. 6 and 7 are perspective views of two forms of bars used in building the preferred form of our dielectric-heating electrode, to which, however, we are not limited.

The embodiment shown in Fig. 1 comprises a pair of opposed generally horizontal electrode-means which are indicated in their entireties by the reference numerals 2 and 4, respectively. These electrode-means are vertically spaced to provide a space therebetween which serves as a work-receiving passage. The electrode-means 4 comprises a horizontal metal plate 6 having turned ends 8. An endless conveyor 10 of insulating material has an upper run which rides on the plate 6. The conveyor is wrapped around drums 12, one of which may be driven by any suitable means to move the upper conveyor-run in an assumed direction shown by the arrow in Fig. 1, at the right. The conveyor carries suitable dielectric material 14 through the work-receiving passage between the electrode-means 2 and 4. The plate 6 and the conveyor 10 form a work-supporting means by means of which the material 14 is supported and carried through the apparatus in a linear travel-path. The material is of less height than the extent of the space between the electrode-means 2 and 4, so that an air-gap 16 is present between the top of the material 14 and the bottom of the electrode-means 2.

The embodiment shown in Fig. 2 comprises generally horizontal opposed electrode-means 2 and 20 which are vertically spaced to provide a work-receiving passage therebetween. The electrode-means 20 comprises a work-supporting means in the form of metal rollers 22 which are rotated by any suitable means for conveying material 24 thereon through the work-passage in the assumed direction indicated by the arrow at the right of Fig. 2. The material 24 may be the same as or different from the material 14. An air-gap 16 is present between the top of the material 24 and the bottom of the electrode-means 2.

The electrode-means 2 is swingably supported. To this end, in Figs. 1 and 2, each of a pair of spaced structural channels 28 swingably supports a pair of spaced support-arms 30 and 32, through pivots 33 that allow the support-arms to swing in planes parallel to the line of travel of the material 14 and 24. The support-arms 30 and 32 may be made either of metal or of insulation, depending on whether the electrode-means 2 is to be grounded or insulated from ground.

Secured to the lower ends of the support-arms 30 and 32 are horizontal stub shafts 34 journaled in suitable fingers 36 which carry a metal frame 38. The frame 38 is part of the electrode-means 2. Accordingly, each point of the electrode-means 2 can swing back or forth in a vertical plane paralleling the direction shown by the arrows in Figs. 1 and 2, in which the work travels. The parallelogram-like support of the electrode-means 2 allows the electrode means to remain in a horizontal plane as it swings. Obviously, cables, wires, etc. will allow for an even greater freedom of swinging and other movement.

The electrode-means 2 also comprises a plurality of support-members 40 dependently car-

ried by the frame 38 and a plurality of electrode-bars pivotally carried by the lower ends of the depending support-members 40 and subsequently described in greater detail.

The main purpose for showing the two embodiments of Figs. 1 and 2 is to illustrate the adaptability of the upper electrode-means 2, which constitutes our novel dielectric-heating electrode, with different forms of lower electrode-means of which the electrode-means 4 and 20 serve as illustrations. Thus, for example, a conveyor, such as 10, can be made of metallic material and itself provide the lower electrode. The showing of the two modifications is also to illustrate the adaptability of the electrode-means 2 for use in different positions with respect to the travel-path of the material to be heat treated, that is, with respect to direction in which the material is moved by any suitable conveyor means. With such travel-path as a fixed reference, it is apparent that the electrode-means 2 is shown in Fig. 1 disposed at a right angle with respect to its showing in Fig. 2.

As is known to the art, in a system set up as shown, the electrode-means 2 is electrically insulated from the electrode-means 4 of Fig. 1 and 20 of Fig. 2. Such relatively insulated relation between the respective pairs of electrode-means can be obtained in any suitable way. As an example, Fig. 1 shows the electrode-means 2 grounded. Consequently, the plate 6 of the electrode-means 4 of Fig. 1 should be insulated from ground, and the support-arms 30 and 32 can be of metal. As a second example, Fig. 2 shows the electrode-means 2 insulated from ground. Consequently, the electrode-means 20 can be separately grounded, as shown at 42, and the support-arms 30 and 32 can be insulated, or made of insulating material, or any other suitable expedient used. Obviously other combinations are possible, as for example the electrode-means 2 of Fig. 1 can be insulated from ground and the plate 6 of the electrode-means 4 grounded. Additionally, instead of a grounded circuit-path, a conductor can be substituted.

Assuming, as shown in Fig. 1, that the plate 6 is insulated, a high-frequency electric field is established between the plate and the electrode-means 2 by electrically connecting power delivering conductors 44 and 46 to the plate 6 and electrode-means 2, respectively. The conductors 44 and 46 receive power, either directly or indirectly, from a high-frequency oscillation-generator 48. The conductor 46 is shown, for convenience, as grounded at 49. For completing the electric circuit, the electrode-means 2 can be grounded either through the members which support it or through a separate grounding conductor connected through a terminal connector associated with the electrode-means in any suitable manner.

The physical construction of the electrode-means 2 is more particularly shown in Figs. 3 through 7. The frame 38 of the electrode-means 2 comprises support-bars in the form of two spaced, lengthwise channels 50 and 52 interconnected by a pair of outer channels 54 and 56 and an inner channel 58. The channels 54, 56 and 58 are provided with slots 60, 62 and 64, respectively, the slots extending lengthwise in the base 66 of the channels centrally between the legs 68 of the channels. Each slot receives a plurality of the support-members 40 which carry a plurality of electrode-bars. The electrode-bars

comprise narrow strips or shapes such as shown in Figs. 6 and 7.

The electrode-bar of Fig. 6 comprises a comparatively short strip 70 having a center hole 72 and a pair of end holes 74 and 76 which are oversize or elongated. The other electrode-bar, shown in Fig. 7, comprises a strip 78 which is approximately twice as long as the strip 70. The strip 78 is provided with a center hole 80 and oversize or elongated holes 82 and 84 at the ends of the strip. The strip 78 has further holes 86 and 88, respectively half way between the holes 80 and 82, and the holes 80 and 84. Preferably, the electrode-bars have rounded edges to avoid sharp points, and their center and end holes are countersunk on their undersides.

As shown in Fig. 3, the electrode-bars or strips are arranged to form a lazy-tong structure. To this end, the strips are arranged in two levels and criss-cross each other. The strips in the lower level comprise the long parallel strips 78 and diagonally opposite short strips 70. The strips in the upper level comprise long parallel strips 78' and diagonally opposite strips 70'. The bottom surfaces of the strips in each level preferably lie in a single plane, within manufacturing and assembly tolerances which in most cases allow considerable leeway.

In the arrangement shown, each lower strip 78, except the one at the upper end of the lazy-tong arrangement, crosses three upper strips 78' at intermediate points along the length of the strip 78, and meets the ends of two strips 78' at end points of the same strip 78. Likewise, an upper strip 78' in effect crosses and meets five lower strips 78. Accordingly, except for the outermost strips, a strip 78 of the lower level of the lazy-tong structure has five junction points with the strips 78' of the upper level, and conversely a similar strip 78' of the upper level of the lazy-tong has five junction points with the lower strips 78. Three of the junction points for such strips are at the channels 54, 56 and 58, and two are centrally between the channels.

Each of the short end-strips 70 and 70' crosses a bar 78 or 78' at a point which is centrally between the inner channel 58 and an outer channel 54 or 56. Each of the end-strips 70 and 70' also has a junction point at its end which is at the channel 58, and a similar point at its end which is at a channel 54 or 56.

The criss-crossed arrangement of the electrode-strips 70, 70', 78 and 78' is carried from the channels 54, 56 and 58 by a plurality of pivot means comprising the support-members 40. A support-member 40 is provided at each junction point of the bar 78 and 78' that lies at a channel 54, 56 or 58. Similar support-members are used at each junction point of the bars 70 and 70' and at the junction points of these bars 70 and 70' and a bar 78 or 78'. In the preferred embodiment, the support-members are substantially alike and are constructed as shown in Fig. 4.

Referring in particular to Fig. 4, a support-member 40 comprises a flathead brass screw 90 having an end that passes through the slot 64 in the channel 58. The lower head-end of the screw passes through aligned holes in the strips 78 and 78', with the head of the screw seating in the countersunk hole in the lower strip 78. A brass washer 92 lies between the crossing electrode-bars. A stop nut 94 presses a spring washer 96 against the top of the upper strip 78' and forces the two strips 78 and 78' into good electrical contact with the brass washer but free enough so that they can twist around the screw 90.

The screw 90 carries a thrust nut 98 slightly above the stop nut 94, a compression spring 100 above the thrust nut, a lower roller means 102 above the spring 100 and below the channel 58, an upper roller means 104 above the channel, and locking nuts 106 and 108.

Each of the roller means 102 and 104 comprises a plate support 110 having a hole through which the screw 68 freely passes, a pair of stub shafts 112 and 114 extending in opposite directions outwardly from the plate support 110, rollers 116 and 118 carried respectively on the stub shafts 112 and 114, and suitable retaining means for holding the rollers on the stub shaft, the retaining means being indicated as cotter pins 120.

By turning the holding nuts 106 and 108, the distance of the electrode-bars 70, 70', 78 and 78' above the lower electrode-means 4 or 20, as the case may be, can be controlled. Moreover, the different junction points of the bars can be individually adjusted so as to make the surface of the electrode-strips as level as convenient or desired. After such adjustment, the thrust nut 98 can be moved to compress the spring 100 so as to determine the force with which the roller means 102 and 104 press against the bottom and top of the channel 58.

To assure good electrical conduction between a channel and the roller means, smooth narrow brass strips 122 are secured to each channel 54, 56 and 58 along each side of the slots therein, coextensive therewith. The strips 122 may be on the upper or on the lower sides of the channels or on both sides. In the embodiments shown, they are only on the lower sides. The rollers 116 and 118 of the lower roller means 102 ride on these strips 122. The electric circuit passes through the rollers to the screws 90 and the strips 70, 70', 78 and 78'.

At each of the junction points of the electrode-strips between the channel members, a pivot means 124 is provided for holding the strips together, and to provide good electrical contact therebetween. A preferred form of construction for such pivot means is shown more particularly in Fig. 5. It comprises a short brass screw 126 which seats in the countersunk seat of a lower electrode-strip, and passes through the crossing strips, being held by a stop nut 128 pressing against a spring washer 130. To allow for greater freedom of movement between the crossing strips and for good electrical contact therebetween, a brass washer 132 can be provided therebetween.

Fig. 3 shows the lazy-tong arrangement of electrode-bars slightly extended. The upper strips 78' are all parallel and equally spaced, having their ends at the slots in the outer channels 54 and 56. These strips are oblique to these channels but deviate only slightly from a perpendicular thereto. The lower strips 78 obliquely cross the upper strips 78' and also have their end points at the slots in the outer channels 54 and 56. The inner channel 58 serves as a further supporting point for each strip. The intermediate pivot points 124 help to prevent sag in the strips at the junction points between channels. The crossing strips provide a perforated electrode-means having a plurality of diamond-shaped openings. The openings are arranged in rows with the openings in a row being staggered with respect to the openings in the adjacent rows, the staggering being such that no straight line can be drawn across the

electrode-means without cutting across an opening. It is also to be noted that each opening provided by the criss-crossed strips has non-uniform lengths at different parts thereof, measured in parallel directions.

Preferably, a large number of strips are provided in order to produce the electrical effect of an electrode-means consisting of a solid metallic sheet. It is known that a perforated metallic sheet can provide the effect of a solid piece of metal for bounding an electric field if the openings in the structure are not too large. In a typical lazy-tong structure, such effect was obtained by using long aluminum strips of close to 60 inches in length, and short aluminum strips slightly more than half that long. The number of strips used correspond to the number shown in Fig. 3, in a frame having dimensions that were approximately 56 inches by 46 inches, the shorter dimensions being that in which the lazy-tong structure could be expanded and contracted. With the arrangement of the electrode-strips in the manner shown, with their flat faces facing the opposed electrode-means 4 or 20 and their narrow edges upstanding, the strips as a whole can be said to lie on the same level when they are spaced far enough from the opposed electrode-means 4 or 20 and they are sufficiently thin. In the specific embodiment described, the strips were $\frac{3}{16}$ inch thick, and the work-receiving passage 1 to 3 inches high.

Obviously, by loosening the thrust nuts 98, the lazy-tong structure can readily be spread out or collapsed for increasing or decreasing the criss-crossed area encompassed by the structure. The nuts can then be retightened. Loosening the nuts 106 and 108 also permits the lazy-tong structure to be extended or contracted, but may require more caution in order not to change the vertical spacing between the electrode-means.

The holes 74, 76, 80, 82 and 84 in the electrode-bars or strips are sufficiently oversize or elongated to allow the lazy-tong electrode-means 2 to be adjusted so as to occupy any desired portion of the area of the frame 38, from a maximum determined by the length of the slots 60, 62 and 64 to a minimum determined by the width of the strips. By adjusting the angle which the strips make with each other, and corresponding with the angle which each strip makes with the channel members of the frame, the effective area for the electrostatic field of the electrode-means 2 is correspondingly changed.

If the electrode-means 2 is arranged as shown in Fig. 1, the overall length of the electrostatic heating field can be changed in the direction of movement of the material 14. Such an arrangement is more likely to be used where the width of the material being heat treated remains fairly constant. If the electrode-means 2 is disposed as shown in Fig. 2, the overall width of the electrostatic heating field can be changed in a direction transverse to that in which the material 24 moves. Such an arrangement is more likely to be used where the width of the material being dielectrically heated will vary from time to time and it is desirable to adjust the electrode-means to a corresponding width. In this latter arrangement, should an arc strike from the material to one of the electrode-strips, it will ultimately reach an opening formed in the criss-cross arrangement of the strips. As the point of origin of the arc moves into the opening, the arc elongates and becomes extinguished. In the meantime, the spot of glue or other material which caused the arc to strike has a chance to become burned out. For such

arc-extinguishing operation, it is desirable to provide a minimum spacing between electrode-strips on the same level, the spacing being such that an opening will always be encountered by an arc 5 moving with the material.

Oblique strips in a single layer only also provide an open space for elongating any arc occurring in the air-gap 16.

If a more direct contact for an electrical circuit 10 to the electrode-means 2 is desired, one or more of the electrode supporting-members 40 can be provided with a terminal connector 134, as shown in Fig. 4. The connector is held in place on a screw 90 by a holding nut 136. The terminal connector 134 receives a conductor 138 which may be insulated or grounded so as to correspond to the conductor 46 of Fig. 1. In order to carry the electricity readily from the connector to the various electrode-strips, the parts of the electrode supporting members 40 that may be called up to carry current are preferably made of brass, and for economy the channels of the frame 38, and the various electrode strips 70, 70', 78 and 78' can be of aluminum.

25 There is a distinct advantage in providing a plurality of support-members 40 for carrying the criss-crossed strips. The relatively elongated screw 90 of each support-member allows for limited vertical adjustment of the levels of the strips 30 70, 70', 78 and 78', through raising or lowering the holding nuts 106 and 108. The nut 98 can be adjusted for a suitable compression of the spring 100.

35 A swinging support for the lazy-tong, such as provided for Fig. 2, and obviously also applicable to Fig. 1, also has a distinct advantage in case any material being dielectrically heated should buckle. The electrode-means 2 can swing when a piece of buckled board should hit it, as may sometimes 40 occur in edge gluing where a plurality of elongated narrow veneers or boards are placed lengthwise on the conveyor means with their upright edges to be glued together. A safety switch such as 140 can stop the conveyor motor through a motor controlling relay 142, when the electrode-means swings. The buckled boards can then be removed, or the electrode-means swing out of the way to permit the boards to pass.

50 While we have described our invention in fairly particular detail, it is obvious that these details are subject to wide variations and that many modifications can be made thereof.

We claim as our invention:

55 1. Dielectric heating apparatus, comprising, in combination, a pair of parallel, generally horizontal, relatively insulated electrode-means vertically spaced to form a work-receiving passage, the upper one of said electrode-means comprising a plurality of elongated obliquely criss-crossed strips having faces lying substantially in a plane, the strips being carried with said faces adapted to bound a high-frequency electric field, fastening means for securing said strips together, and conductor means for applying high-frequency power between said pair of electrode-means.

60 2. Dielectric heating apparatus adapted for the continuous gluing of veneers of wood, comprising, in combination, a lower work-supporting conveyor means comprising a lower electrode-means, said conveyor means being adapted to move wood in a predetermined linear travel-path therealong, a plurality of metallic strips having narrow edges and flat faces, supporting means supporting said strips along the top of said travel-path with the strip-edges upstanding and the strip-faces lying

in a substantially flat surface paralleling said path, said supporting means supporting said strips so that they are horizontally spaced and substantially parallel but are oblique to said travel-path, said supporting means comprising adjustable mechanism for changing the spacing between said strips and for raising and lowering them, and means for relatively insulating said lower electrode-means and said strips.

3. Dielectric heating apparatus adapted for the continuous gluing of veneers of wood comprising, in combination, a lower work-supporting conveyor means comprising a lower electrode-means, said conveyor means being adapted to move wood in a travel-path therealong, a frame above said conveyor means, said frame comprising a plurality of spaced elongated support-bars, a plurality of metallic electrode-strips having flat surfaces, and pivot means associated with said support-bars and said electrode-strips, and carrying said electrode-strips from said support-bars in a lazy-tong arrangement, with the flat surfaces of the strips facing said conveyor means.

4. An invention including that of claim 3 but further characterized by supporting means swingingly carrying said frame above said lower electrode-means.

5. Dielectric heating apparatus adapted for the continuous gluing of veneers of wood comprising, in combination, a lower work-supporting conveyor means comprising a lower electrode-means, said conveyor means being adapted to move wood in a travel-path therealong, a frame above said conveyor means, said frame comprising a plurality of spaced elongated support-bars, each of said support-bars having a central elongated slot therein, a plurality of spaced pivot means including pivots in each of said slots, said pivots being slidable in the slots, said pivot means including means for fixing said pivots in selected positions in said slots, a plurality of electrode-bars carried by said pivots in a lazy-tong arrangement, said lower electrode-means and said electrode-bars being relatively insulated, and means comprising a terminal connection for the supply of high-frequency power to said electrode-bars.

6. A dielectric-heating electrode comprising a supporting-bar, a plurality of strips, support means for supporting said strips from said supporting bar with the strips in spaced parallel relation to each other but oblique to said supporting bar, said strips having faces directed in the same general direction and adapted to be the boundary of a high-frequency electric field, said support-means being adjustable to vary the spacing between said strips.

7. A dielectric-heating electrode comprising a plurality of obliquely criss-crossed strips electrically interconnected, said criss-crossed strips being adjustable to vary the angle of oblique crossing of the strips and to vary the spacing between said strips, and a terminal on said dielectric-heating electrode.

8. A dielectric-heating electrode comprising a plurality of layers of spaced parallel metallic strips, the strips of each layer having faces adapted to bound an electric field and lying substantially in a plane, the strips of a first layer crossing the strips of a second layer, and clamping pivot means at the crossing points of said strips, said strips being electrically interconnected.

9. A dielectric-heating electrode comprising a plurality of layers of spaced parallel strips, the strips of each layer having faces adapted to

bound an electric field and lying substantially in a plane, the strips of a first layer crossing the strips of a second layer, and fastening means securing the strips together, said fastening means comprising loosenable support-members for changing the angle between crossing strips.

10. A dielectric-heating electrode comprising a frame having a plurality of parallel elongated spaced support-bars, a plurality of elongated electrode-bars, support-members adjustably securing a first end of each of said electrode-bars to a first of said support-bars and the opposite end to a second of said support-bars, with the electrode-bars remaining parallel and equally spaced with respect to each other in all of the adjusted positions thereof, said electrode-bars having faces lying substantially in a plane, and being oblique to said support-bars.

11. A dielectric-heating electrode comprising a frame having a pair of outer support-bars and an inner support-bar therebetween, said support-bars being spaced and parallel on the same general level, a plurality of first electrode-bars extending from and between said outer support-bars, a plurality of second electrode-bars from and between said inner support-bar and said outer support-bars, said electrode-bars being crossed, said electrode-bars being in electrically linked relation.

12. A dielectric-heating electrode comprising a frame having a pair of outer support-bars and an inner support-bar therebetween, said support-bars being spaced and parallel on the same general level, said support-bars having slots along their lengths, pivot means adjustably positionable in said slots, and extending below said support-bars, said pivot means comprising roller means rollable on the support-bars, a plurality of metallic strips carried by said pivot means below said rollers with the strips in lazy-tong arrangement, certain of said strips extending from and between said outer support-bars, and means for passing electricity to said strips.

13. A dielectric-heating electrode comprising a frame having a pair of outer support-bars and an inner support-bar therebetween, said support-bars being spaced and parallel on the same general level, said support-bars having slots along their lengths, pivot means adjustably positionable in said slots, and extending below said support-bars, a plurality of metallic strips carried by said pivot means below said support-bars, said pivot means comprising electricity conducting members electrically roller connected to said strips, and comprising means for vertically adjusting said strips.

14. An adjustable dielectric-heating electrode comprising a supporting bar having an elongated slot, pivot means adjustably positionable in said slot, and extending below said supporting bar, said pivot means comprising roller means rollable on said supporting bar, a plurality of metallic strips carried by said pivot means in lazy-tong arrangement below said roller means, said supporting bar comprising a high-conductivity member on which said roller means can roll.

15. An invention including that of claim 12 but further characterized by said pivot means comprising a plurality of vertical members carrying said strips, and means for vertically adjusting said members with respect to said supporting bar.

16. A dielectric heating-electrode comprising a plurality of spaced elongated obliquely criss-crossed electrode-bars arranged in a plurality of

11

superimposed levels, conducting junction means at the crossing points of said bars, and supporting means movably supporting said bars for limited movement in a general direction maintaining the associated bars in their common level, the movement raising said levels.

17. An invention including that of claim 15 but characterized further by said bars being criss-crossed.
